CLAIM

The ornamental design for an adjustable pillow support, as shown and described.

DESCRIPTION

FIG. 1 is a perspective view of a first variant of the adjustable pillow support including a platform and legs supporting said platform;

FIG. 2 is a perspective view of the adjustable pillow support of FIG. 1 showing a pillow on top of the platform as part of the environment;

FIG. 3 is a perspective view of the adjustable pillow support of FIG. 1 showing a pillow on top of the platform as part of the design;

FIG. 4 is a top view of the adjustable pillow support of FIG. 1;

FIG. 5 is a rear view of the adjustable pillow support of FIG. 1;

FIG. 6 is a left-side view of the adjustable pillow support of FIG. 1;

FIG. 7 is a right-side view of the adjustable pillow support of FIG. 1;

FIG. 8 is a front view of the adjustable pillow support of FIG. 1;

FIG. 9 is a bottom view of the adjustable pillow support of FIG. 1;

FIG. 10 is a perspective view of the adjustable pillow support of FIG. 1 showing the legs in an extended position;

FIG. 11 is an exploded view of the adjustable pillow support of FIG. 1 showing the legs detached from the platform;

FIG. 12 is a perspective view of the adjustable pillow support of FIG. 1 showing a pillow enveloping the platform;

FIG. 13 is a perspective view of a second variant of the adjustable pillow support including a platform and legs supporting said platform;

FIG. 14 is a perspective view of the adjustable pillow support of FIG. 13 showing a pillow on top of the platform as part of the environment;

FIG. 15 is a perspective view of the adjustable pillow support of FIG. 13 showing a pillow on top of the platform as part of the design;

FIG. 16 is a top view of the adjustable pillow support of FIG. 13;

FIG. 17 is a rear view of the adjustable pillow support of FIG. 13;

FIG. 18 is a left-side view of the adjustable pillow support of FIG. 13;

FIG. 19 is a right-side view of the adjustable pillow support of FIG. 13;

FIG. 20 is a front view of the adjustable pillow support of FIG. 13;

(Continued)

FIG. 21 is a bottom view of the adjustable pillow support of FIG. 13;

FIG. 22 is a perspective view of the adjustable pillow support of FIG. 13 showing the legs in an extended position; FIG. 23 is an exploded view of the adjustable pillow support of FIG. 13 showing the legs detached from the platform; FIG. 24 is a perspective view of the adjustable pillow support of FIG. 13 showing a pillow enveloping the platform;

FIG. 25 is a perspective view of a third variant of the adjustable pillow support including a platform and legs supporting said platform;

FIG. 26 is a perspective view of the adjustable pillow support of FIG. 25 showing a pillow on top of the platform as part of the environment;

FIG. 27 is a perspective view of the adjustable pillow support of FIG. 25 showing the pillow on top the platform as part of the design;

FIG. 28 is a top view of the adjustable pillow support of FIG. 25;

FIG. 29 is a rear view of the adjustable pillow support of FIG. 25;

FIG. 30 is a left-side view of the adjustable pillow support of FIG. 25;

FIG. 31 is a right-side view of the adjustable pillow support of FIG. 25;

FIG. 32 is a front view of the adjustable pillow support of FIG. 25;

FIG. 33 is a bottom view of the adjustable pillow support of FIG. 25;

FIG. 34 is a perspective view of the adjustable pillow support of FIG. 25 showing the legs in an extended position;

FIG. 35 is an exploded view of the adjustable pillow support of FIG. 25 showing the legs detached from the platform; and,

FIG. 36 is a perspective view of the adjustable pillow support of FIG. 25 showing a pillow enveloping the platform.

The broken lines depict portions of the article that form no part of the claimed design.
